UNITED STATES PATENT OFFICE

SAMUEL BERGSTEIN, OF MIDDLETOWN, OHIO, ASSIGNOR TO THE INTERSTATE FOLDING BOX COMPANY, OF MIDDLETOWN, OHIO

MACHINE FOR MAKING PAPER BOXES OR THE LIKE

Application filed December 4, 1929. Serial No. 411,611.

This invention relates to improvements in machines for making paper boxes, the improvements being a development of the machines set forth in my copending application for patents, Serial #311,859, filed October 11, 1928 and Serial #360,767, filed May 6, 1929.

The machine consists of an arrangement of a relatively fixed die and a series of movable dies which move progressively into operating relation with the fixed die, the box blanks being moved singly to the fixed die in the required order for forming the boxes by the coaction of the dies. The movable dies are supported on a rotatable die carrier and are moved through a circle, being equally spaced one from another so that the box forming operations occur in regular sequence.

An object attained in the improvements herein set forth consists in the provision of means in the fixed die which effect compensating adjustments of the die to the arc of movement of the movable dies during the box forming operations. This arrangement also adapts the dies for a greater range of box sizes, having particular reference to the depth of the boxes.

A further object attained in the invention consists in means provided in the dies for effecting lateral foldings coincident with vertical foldings of the box blanks.

The machine as set forth is organized for large output, the machine structure being compact and durable, and comprised of mechanism which will not readily get out of order.

In the accompanying drawings:

Fig. 1 is a view in side elevation of the machine;

Figs. 2, 3, 4 and 5 are front, rear, end and top views respectively of the fixed die;

Fig. 6 is a sectional view on line 6—6 of Fig. 5;

Fig. 7 is a sectional view on line 7—7 of Fig. 5;

Figs. 8 and 9 are front and end views respectively of a movable die;

Fig. 10 is a broken front view of a movable die;

Fig. 11 is a view of a box blank;

Fig. 12 is a sectional view looking toward an inner end of the box.

Fig. 13 is an end view of the pressure sealing mechanism illustrated in Fig. 1.

The die end of the machine structure consists in a supporting frame 15 which is provided with a suitable base for supporting the stationary die —A, and with a rotatable carrier 18 for the movable dies —B. Carrier 18 is driven by a motor 19 through a chain drive 20, worm gears 21 and a gear train 22, 23, 24, 25. The feeding mechanism for the box blanks is driven from the motor 19 through gearing 20—23 and a chain drive 26, 27, 28.

The feeding mechanism for the box blanks is of a well known type, consisting of a table 29 for supporting a stack of blanks —C, upper and lower feed rolls 31—32, the lower roll being traversed by a belt carrier 33 which contacts with a unit of tensioning feed rolls 34, and a series of carrier supporting rolls 35 for moving the box blanks singly to the stationary die —A.

Means for applying adhesive to the box blanks for forming the box structure are indicated at —D. The illustration in Fig. 1 of the machine structure for delivering the box blanks to the dies, including the mechanism for applying adhesive to the blanks, is of well known character in the art to which the invention relates and is shown conventionally only for illustrating the invention in one form.

The improvements comprised in the invention relate to the stationary and movable dies and consist particularly in the provision of means in the stationary die which cause the die to expand and contract to compensate for the arc through which the movable dies are rotated in the operation of forming the boxes.

The structure of the stationary die consists of a base 36 which is fixed on the frame of the machine and has a rectangular opening 37 and a laterally extended opening 38 through the inner side wall of the base to provide clearance for the movable dies as they pass through operating relation with the stationary die.

Supported slidably on base 36 on opposite sides of the opening 37 are die members consisting of vertical portions 39 which form the side walls of the stationary die, and base 100

plates 40 which are formed integrally with the walls 39 and extend laterally outward therefrom, the plates being retained on base 36 by guides 41 which are secured to base 36 5 and overlap the ends of plates 40.

Members 39-40 are spring tensioned inward by springs 42 supported on stems 43 which are fixed to parts 39 and are slideable in brackets 44, springs 42 being compressed 10 between the brackets and parts 39. The extent of inward movement of the slideable parts 39-40 on the outer section of the die is regulated by adjusting screws 45 supported in brackets 46, the outward movement of parts 15 39-40 on both sides of the die being yieldable to the pressure of the movable dies as they pass through the stationary die, thus compensating for the arc of movement of the movable dies in the operation of forming a 20 box and the variable pressure on the stationary die that results from it. The inner die members 39-40 are in two sections, being spaced one from the other to register with the opening 38 to provide clearance for the 25 movable dies.

The end walls 47 of the stationary die are fixed on base 36. The end walls are slotted vertically on their inner faces as indicated at 47a for receiving fingers 48 which are pivoted 30 at 49 on the under side of base 36, the fingers being tensioned inward by springs 49a and provided with extensions 50, which are engaged by the movable dies for actuating the fingers to effect a folding operation on the 35 box blanks. Spring blades 51 arranged on the inner faces of parts 39 and extended below the stationary die act to sustain the formed box on the movable dies as the boxes are moved along to the pressure sealing devices. Fingers 39a extended upward from 40 members 39 also function in the operations of forming the boxes as will presently be described.

The structure of the movable dies consist in 45 a head member 52 secured to an arm 18 of the rotatable die carrier -B, the opposite ends of parts 52 being offset for supporting members 53, the side and end faces of which are flush with the adjacent faces of members 52, parts 50 53 being pivoted on members 52 as indicated at 54, members 52 being recessed on their under side for effecting the assembly. Parts 53 are connected one with the other by a spring 55 which acts to tension the parts downward. 55 Slots 56 in the ends of members 52-53 provide operating clearance for fingers 48 when the dies are in the operating relation with the stationary die. Fingers 57 secured to members 53 are engaged by pins 58 supported in brackets 59 which acts to move members 53 upward on their pivots 54, springs 55 acting to retract the members to normal position. 60

The operation of forming a box is as follows:

65 The box blank 61 is delivered over the sta-

tionary die in the position indicated, the side portions -a of the blank being directly over the side walls 39, the portions -b over the end walls 47, and the end flaps -c resting on the folding fingers 39a. When one of the movable dies engages the blank and forces it through the stationary die walls 39 act to fold sides -a upward at right angles, fingers 39a acting in advance of the folding of the sides -a to fold flaps -c at right angles to the 70 sides, and walls 47 acting to fold flaps -b upward at right angles. As the movable die progresses through the forming operation fingers 57 of members 53 of the movable die are engaged by pins 58 which act to move members 53 upward for opening the die at the 75 ends. The die then engages extensions 50 of fingers 48 and actuates the fingers inward which acts to fold the outer portions -d of ends -b of the blank inward at right angles 80 to portions -b. Upon die members 53 passing out of engagement with pins 58, springs 55 act to return members 53 to normal position, the further movement of the dies acting to complete the fold of portions -d against 85 the inner face of the box. This latter movement also acts to fold flaps -e against the 90 inner faces of sides -a.

The formed boxes remain on the movable dies as the dies move into engagement with 95 the pressure sealing mechanism which consists of opposite series of pressure rollers 60 arranged in the arc of movement of the dies. Rollers 60 are supported in frames 61 which may be spring-tensioned and adjusted laterally of the machine in any suitable manner according to the size of the movable dies, 100 which is determined by the size of the boxes.

In view of the end flaps -d and corner reinforcing flaps -e the boxes require pressure 105 sealing on four faces, the rollers 60 acting to seal flaps -d to the inner end faces of the box, and opposite series of spring blades 62 acting to seal flaps -e to the inner side faces at the upper corners of the box. The boxes 110 are removed from the dies as they pass from the pressure sealing mechanism by any suitable means, such as the brush 63.

I claim as my invention:

1. A machine for making paper boxes including a die member movable through an arc into operating relation with a relatively stationary die yieldable to the pressure of the movable die when the dies are in said relation to compensate for the arc of movement 115 of the movable die, and means for applying adhesive to box blanks and for positioning the blanks relative to the stationary die, preliminary to forming the boxes by the coaction 120 of said dies.

2. A machine for making paper boxes including a die member movable through an arc into operating relation with a relatively stationary die yieldable under tension to the 125 pressure of the movable die member when 130

the dies are in said relation to compensate for the arc of movement of the movable die, and means for applying adhesive to box blanks and for positioning the blanks relative to the stationary die preliminary to forming the boxes by the coaction of said dies.

3. A machine for making paper boxes including a die member movable through an arc into operating relation with a relatively stationary die yieldable under tension outward oppositely from the center of the die to the pressure of the movable die when the dies are in said relation to compensate for the arc of movement of the movable die and means for applying adhesive to box blanks and for positioning the blanks relative to the stationary die preliminary to forming the boxes by the coaction of said dies.

20 4. A machine for making paper boxes including a die member movable through an arc into operating relation with a relatively stationary die having opposite walls tensioned toward the center of the die and yieldable outward to the pressure of the movable die when the dies are in said relation to compensate for the arc of movement of the movable die and means for applying adhesive to box blanks and for positioning the blanks relative to the stationary die preliminary to forming the boxes by the coaction of said dies.

25 5. A machine for making paper boxes including a die member movable through an arc into operating relation with a relatively stationary die having end walls, and side walls tensioned toward the center of the die and yieldable outward to the pressure of the movable die when the dies are in said relation to compensate for the arc of movement of the movable die and means for applying adhesive to box blanks and for positioning the blanks relative to the stationary die preliminary to forming the boxes by the coaction of said dies.

30 6. A machine for making paper boxes including a die member movable through an arc into operating relation with a relatively stationary die having opposite walls tensioned toward the center of the die and yieldable outward to the pressure of the movable die when the dies are in said relation to compensate for the arc of movement of the movable die and means for applying adhesive to box blanks and for positioning the blanks relative to the stationary die preliminary to forming the boxes by the coaction of said dies.

35 7. A machine for making paper boxes including a die member movable through an arc into operating relation with a relatively stationary die having end walls, and side walls tensioned toward the center of the die and yieldable outward to the pressure of the movable die when the dies are in said relation to compensate for the arc of movement of the movable die, means for adjusting said walls for limiting said inward movement thereof, and means for applying adhesive to box blanks and for positioning the blanks relative to the stationary die preliminary to forming the boxes by the coaction of said dies.

40 8. A machine for making paper boxes including a die member movable through an arc into operating relation with a relatively stationary die having end walls, and side walls tensioned toward the center of the die and yieldable outward to the pressure of the movable die when the dies are in said relation to compensate for the arc of movement of the movable die and means for applying adhesive to box blanks and for positioning the blanks relative to the stationary die preliminary to forming the boxes by the coaction of said dies.

45 movable die when the dies are in said relation to compensate for the arc of movement of the movable die, devices operably associated with said end walls and coacting with the movable die for effecting foldings of box blanks, and means for applying adhesive to box blanks and for positioning the blanks relative to the stationary die preliminary to forming the boxes by the coaction of said dies.

50 9. A machine for making paper boxes including a die member movable through an arc into operating relation with a relatively stationary die having end walls, and side walls tensioned toward the center of the die and yieldable outward to the pressure of the movable die when the dies are coacting one with the other to compensate for the arc of movement of the movable die, said walls acting to effect initial foldings of box blanks, devices operably associated with said end walls and coacting with the movable die for effecting further foldings of the box blanks, and means for applying adhesive to box blanks and for positioning the blanks relative to the stationary die preliminary to forming the boxes by the coaction of said dies.

55 10. A machine for making paper boxes including a die member movable through an arc into operating relation with a relatively stationary die having opposite walls tensioned toward the center of the die and yieldable outward to the pressure of the movable die when the dies are coacting one with the other to compensate for the arc of movement of the movable die, devices tensioned toward the center of the die acting to support the box blanks during the operation of the dies for forming boxes, and means for applying adhesive to box blanks and for positioning the blanks relative to the stationary die preliminary to forming the boxes by the coaction of said dies.

60 11. A machine for making paper boxes including a relatively stationary die having a part operable for effecting a folding of a box blank, a movable die including a part operable for providing clearance in the movable die for said portion of the box blank as it is being folded, and means for applying adhesive to box blanks and for positioning the blanks relative to the stationary die preliminary to forming the boxes by the coaction of said dies.

65 12. A machine for making paper boxes including a relatively stationary die having a part operable for effecting a folding of a box blank, a movable die acting to operate said part and having a part operable for providing clearance in the movable die for said portion of the box blank as it is being folded, and means for applying adhesive to box blanks and for positioning the blanks relative to the stationary die preliminary to forming the boxes by the coaction of said dies.

forming the boxes by the coaction of said dies.

12. A machine for making paper boxes including a relatively stationary die having a part operable for effecting a folding of a box blank, an actuator fixed relative to said die, a movable die acting to operate said part and having a part operated by said actuator for providing clearance in the movable die for said portion of the box blank as it is being folded, and means for applying adhesive to box blanks and for positioning the blanks relative to the stationary die preliminary to forming the boxes by the coaction of said dies.
13. A machine for making paper boxes including a relatively stationary die having a part operable for effecting a folding of a box blank, an actuator in fixed relation to said die, a movable die acting to operate said part and having a part spring tensioned in normal relation and operable by said actuator for providing clearance in the movable die for said portion of the box blank as it is being folded, and means for applying adhesive to box blanks and for positioning the blanks relative to the stationary die preliminary to forming the boxes by the coaction of said dies.
14. A machine for making paper boxes including a relatively stationary die having a part operable for effecting a partial folding of a box blank, a movable die acting to operate said part and having a part operable for providing clearance in the movable die for said portion of the box blank as it is being folded, said part of the movable die acting to complete said fold of the box blank, and means for applying adhesive to box blanks and for positioning the blanks relative to the stationary die preliminary to forming of the boxes by the coaction of said dies.
15. A machine for making paper boxes including a relatively stationary die having a part operable for effecting a partial folding of a box blank, a die movable in the plane of said part and having operating clearance therefor, said movable die including a part operable for providing clearance in the movable die for said portion of the box blank as it is being folded, said part of the movable die acting to complete said fold of the box blank, and means for applying adhesive to box blanks and for positioning the blanks relative to the stationary die preliminary to forming the boxes by the coaction of said dies.

In testimony whereof, I affix my signature.
SAMUEL BERGSTEIN.
